TREATING APPARATUS

Mead Cornell, Cleveland, Ohio, assignor to The Cornell Machine Company, Cleveland, Ohio, a corporation of Ohio

Application July 31, 1940, Serial No. 348,851

3 Claims. (Cl. 259—96)

This invention relates to a method and apparatus for treating or mixing materials, and more particularly, to improvements in the method and apparatus involving the use of the homogenizer construction illustrated and described in my Letters Patent No. 2,042,880 issued June 2, 1936.

In my afore-mentioned Letters Patent, there is disclosed a homogenizer which involves the use of a rapidly rotating annular member or disk. The material to be mixed is fed centrally of the rotating member and is delivered onto the surface thereof in a continuous film. This film is then centrifugally attenuated by the rotating disk and the attenuated film is collected from the outer peripheral edge of the rotating member, the construction being such that the continuity of the film is not broken from the time that it is fed onto the surface of the rotating member until it is projected from the outer peripheral edge of the rotating member.

The use of apparatus of the character referred to has proven highly successful, but such apparatus is not readily adaptable to the mixing of certain immiscible materials wherein one of the materials, at least, has a consistency or viscosity relatively high as compared to other of the materials being mixed. For example, my apparatus, wherein the materials to be mixed are fed into a common manifold from separate sources, is not readily adaptable to the preparation of certain asphalt mixtures used in connection with highway construction. A common type of such an asphalt mixture comprises a mixture of asphalt and naphtha, the asphalt being pre-heated to a temperature of from 250 to 400° F. to render the same more workable and then mixed with naphtha which is introduced at room temperature to reduce the consistency of the asphalt in order that the same may be readily placed on a road bed in construction work.

Due to the wide divergence in the viscosities or consistencies of materials such as naphtha and heated asphalt, difficulties would be encountered in the feeding of a continuous film of the mixture to the rotating disk of my prior apparatus for an attenuating and homogenizing action. I have found that the employment of mixing apparatus to provide an unstable mixture of the materials to be mixed largely eliminates the difficulties of the prior art and readily adapts a homogenizer of the character referred to for use with such materials. In other words, the use of mixing apparatus to form an unstable mixture of two or more immiscible liquids having widely divergent viscosities enables the employ-

ment of a homogenizer of the character referred to for converting the unstable mixture of immiscible materials into a substantially permanent and homogeneous mixture.

Accordingly, one of the principal objects of this invention is to adapt a mixer, of the type employing a rapidly rotating disk to form an attenuated film, for use with immiscible materials having widely divergent consistencies or viscosities by the provision of pre-mixing apparatus to form an intimate but unstable mixture of the materials prior to their being fed to the rapidly rotating disk.

A further object of this invention is the provision of a homogenizer employing a plurality of rotating disks onto which the material to be mixed may be fed for an attenuating action.

A further object is to provide, in a homogenizer of the character referred to, a novel arrangement of mechanism for simultaneously feeding the material to the rotating disks.

A further object is to provide, in a homogenizer of the character referred to, a novel arrangement of collecting devices against which the attenuated film may be projected and conducted away without interrupting the continuity of the attenuated film.

Other objects and advantages of the invention will become apparent during the course of the following description.

To the accomplishment of the foregoing and related ends, the invention, then, comprises the features hereinafter fully described, and particularly pointed out in the claims, the following description and the annexed drawings setting forth in detail certain illustrative embodiments of the invention, these being indicative however, of but a few of the various ways in which the principle of the invention may be employed.

In the drawings, there is shown several preferred embodiments of the invention. In the showing,

Fig. 1 is a side elevational view of one form of the invention, parts thereof having been broken away, and diagrammatically showing an electrical motor control hook-up;

Fig. 2 is an enlarged vertical sectional view of the homogenizer unit shown in Fig. 1, parts thereof having been broken away;

Fig. 3 is a side elevational view of a modified form of the invention provided with a pre-mixing device; and

Fig. 4 is an enlarged vertical sectional view of the apparatus shown in Fig. 3, parts thereof having been broken away.

Referring to the drawings, the numeral 1 indicates as a whole a homogenizer unit comprising a hollow cylindrical container 2 having a top 3 and a bottom 4. An opening 5 is formed in the top 3 through which a drive shaft 6 extends, the drive shaft 6 being provided with an axial thrust bearing assembly 7 carried by a bearing housing 8. The drive shaft 6 is driven from a motor 9 carried by a motor support 10 mounted on the bearing housing 8, a suitable connection 11 being provided for connecting the motor shaft to the upper end of the drive shaft 6.

A hollow drive shaft 12 is rigidly secured to the drive shaft 6 for rotation thereby and extends upwardly through the opening 5. A stuffing box and packing gland indicated as a whole by the numeral 13 (see Fig. 4) is provided for sealing the shaft 12 in the opening 5.

A plurality of centrifugal disks or annular rotating members 14 are rigidly secured in spaced vertical relation on the hollow shaft 12 for rotation thereby. The construction and operation of each of the centrifugal disks 14 is substantially the same as shown in my afore-mentioned patent to which reference is made for a more particular description. For the purposes of this description, it will be sufficient to point out that the disks 14 are dish-shaped and project radially outwardly and axially upwardly from the sleeves 15 by which they are secured to the shaft 12. Guard or deflector rings 16 are concentrically positioned with respect to the shaft 12 by means of spacer rings 17 mounted on the shaft 12. The fit between the deflector rings 16 and spacer rings 17 is relatively free to permit axial and rotational movement of the deflector rings relative to the hollow shaft 12. The bottom portion of the deflector rings 16 are provided with annular flanges 18 which have a dish-shape opposed to that of the centrifugal disks 14 to provide spaces 19 at the inner peripheral edge of the centrifugal disks 14.

The outer peripheral edges of the flanges 18 are adapted to abut against the inner peripheral surface of the centrifugal disks 14 to limit downward movement of the rings 16 with respect to the shaft 12 and also operate to impound a quantity of the material to be acted upon in the spaces 19, the material to be mixed being delivered to the spaces 19 through aligned openings 20 formed in the shaft 12 and sleeves 15. With material being delivered to and confined in the spaces 19, such material will be fed onto the surface of the centrifugal disks 14 in a continuous film upon rotational movement being imparted to the shaft 12 and disks 14, the rings 16 moving upwardly in a manner well known in the art to permit this action.

When the disks 14 rotate at high speed, the film delivered to the upper surface thereof will be thrown radially outwardly and axially upwardly by centrifugal force. The construction of the disks 14 is such that the axial displacement of the film will be small as compared to the radial displacement and the film will be maintained in contact with the upper surface of the disks 14 while mechanically supported on one side only and will be projected from the outer peripheral edges of the disks 14 in a film of extreme thinness.

To collect the film projected from the outer peripheral edges of the disks 14, an annular deflector ring 21 is provided for each disk 14. The deflector rings 21 are mounted in spaced vertical relation by means of brackets 22 secured to sup-

porting members 23 which are in turn secured to the inner side of the cylindrical container 2. The deflector rings 21 are curved so as to slope outwardly and downwardly with respect to the container 2 in order that the film being projected from the disks 14 will impinge against the inner surface 24 of the rings. The film thus projected against the rings 21 will be deflected downwardly and drop down to the bottom of the vessel. The deflector rings 21 are mounted so as to provide a space 25 between the outer peripheral edges of the disks 21 and the inner surface of the wall of the container 2. In this manner, each of the deflector rings is operable to direct the film from its associated disk 14 to the bottom of the vessel without interrupting the continuity of the film being projected from other of the rotating disks 14. Any material falling from one of the deflector rings 21 will strike the upper surface of the next lower deflecting ring 21 so as to be directed inwardly toward the side of the vessel thereby preventing such falling material from interrupting the continuity of the film being projected from underlying disks 14.

Referring particularly to Figs. 1 and 2, it will be noted that the hollow shaft 12 projects through an opening in the bottom 4 of the casing and a suitable packing device 26 is provided for sealing the shaft in this opening. An axial thrust bearing assembly 27 and housing 28' is provided for rotatably supporting the bottom portion of the shaft 12. In this particular showing, the material to be mixed is forced from a suitably electrically driven pump 28 through a conduit 29 to the interior of the shaft 12, the conduit 29 being provided with a fluid-tight connection 30 with the shaft 12. In this manner, the material to be mixed may be forced by the pump 28 upwardly through the hollow shaft 12 and thence through the openings 20 onto the disks 14 for the final mixing action.

A discharge conduit 33 is provided for withdrawing the homogenized mixture through an opening 34 formed in the bottom 4 of the container 2. The conduit 33 is connected to an electrically driven discharge pump 35 which is preferably operated at a rate of speed sufficient to withdraw mixed fluid at the same rate of speed as unmixed fluid is being supplied by the supply pump 28. The pumps 28 and 35 are thus operated to maintain a constant level of mixed fluid in the bottom of the container 2 which is particularly desirable when the mixing is taking place in a vacuum, a connection 36 being provided for connecting the interior of the container 2 with suitable apparatus (not shown) for maintaining a vacuum within the interior of the container 2.

To prevent either the motors 28 or 35 from getting ahead of each other and thereby interfering with the level of fluid to be maintained in the bottom of the container 2, the motors 28 and 35 are respectively provided with solenoid control switches 36 and 37. The switches 36 and 37 are preferably biased to a closed position to maintain the motors 28 and 35 in operation. Upon completion of the electrical circuit to either of the solenoid switches 36 or 37, such switches will be opened to interrupt the operation of the motors with which they are associated. A control switch 38 is provided for operating the electrical circuits to the solenoid switches 36 and 37. The switch 38 is operated by means of a float 39 positioned interiorly of the container 2 through a suitable linkage connection including the bell-crank lever 40 for imparting a reciprocatory

motion to the operating member 41 for the contact 38 upon upward or downward movement of the float 39. In this manner, when the level of fluid in the container 2 drops below a desired point, the float 39 will move downwardly to effect an inward movement of the switch control 38 through the member 41 to complete the circuit through the solenoid switch 37 to interrupt the action of the discharge motor 35. Likewise, when the level of the mixture in the container 2 rises above a desired point, the control switch 38 will be caused to complete the circuit to the solenoid control switch 36 to cause an interruption of the supply motor 28 in order to interrupt the supply of materials to the container 2.

Referring particularly to Figs. 3 and 4, it will be noted that the construction illustrated in these figures is the same as for Figs. 1 and 2 except for the mounting of the bottom of the hollow shaft 12 and the manner in which the material is fed to the shaft 12. In this construction, the bottom of the shaft 12 is mounted for rotation interiorly of the container 2 by a bearing assembly 42 carried by a sput connection 43 mounted on a tubular member 44. Packing 45 is employed to provide a fluid seal for the end of the shaft 12 in the mouth of the sput 43. The cylinder 44 provides a casing for mixing apparatus of the type illustrated and described in Lichtenhaeler Patent No. 1,496,345 to which reference is made for a more detailed description. Within the mixing chamber provided by the cylindrical member 44 is mounted a perforated sparger 46. Liquid may be fed to the sparger 46 by a conduit 48 extending through an opening formed in a plate 47 closing one end of the cylinder 44. The other end of the cylinder 44 is open as at 48 for the admission of the material to be mixed with the fluid being supplied through the conduit 46. The sparger 45 is provided with a spiral or helical vane 49 spacing the same from the interior of the cylinder 44. In this manner a tortuous path is provided for the material entering at 48 and a whirling agitating movement will be imparted to this material as it moves over the perforated surface of the sparger 45. Upon feeding materials simultaneously through the conduit 46 and opening 48, these materials will be intimately mixed prior to being forced upwardly through the interior of the hollow shaft 12 for feeding onto the rotating disks 14.

The apparatus illustrated in Figs. 3 and 4 is particularly well adapted for use in mixing materials such as asphalt and naphtha. The asphalt is first heated and then forced through the opening 48 while the naphtha is being fed through the conduit 46. The naphtha is fed at room temperature and ordinarily has a boiling point of from 275 to 300° F. which is substantially equal to or less than the preferred temperature at which the heated asphalt is fed. In this manner, the naphtha will be sprayed into the asphalt to form an intimate but unstable mixture of the asphalt and naphtha. This unstable mixture will then be forced upwardly by the pressure of the materials being fed through the opening 48 and conduit 46 through the interior of the shaft 12 and outwardly onto the disks 14 in a condition which will enable the rotating disks to complete the mixing action by converting the unstable mixture into a substantially stable and permanent mixture.

The provision of the pre-mixer in the casing 44 enables the mixing function provided by the

attenuating action of the rapidly rotating disks 14 to be employed for a wide variety of materials which would otherwise have to be mixed by other types of apparatus. Although this pre-mixer has been described in connection with the mixing of materials such as asphalt and naphtha, it will be understood that the invention involving the use of the pre-mixer may be employed for materials, other than asphalt and naphtha, which have widely divergent consistencies or viscosity characteristics.

The operation of the apparatus will be apparent from the foregoing, and it is sufficient to point out that the operation of the disks 14 and associated parts to provide the attenuating mixing action will be the same whether the material to be mixed is supplied from the pump 28 or from the pre-mixer in the casing 44. The apparatus of Figs. 3 and 4, while specifically adapted for use with materials having widely divergent viscosity characteristics, may also be employed for mixing materials of the character for which the apparatus disclosed in my afore-mentioned patent was designed. It will also be noted that the apparatus of Figs. 1 and 2 is particularly adapted for use in connection with the same types of materials, such as in the blending of lubricating oils having different densities, as in the apparatus of my afore-mentioned patent. In connection with the use of the apparatus of this invention, it will be understood that the apparatus disclosed in Figs. 1 to 4 represents an improvement over the construction illustrated in my prior patent in that the provision of a plurality of rotating disks 14 and associated parts, including the mechanism for simultaneously rotating and feeding the material to the disks 14, increases the production capacity without the necessity of a material increase in the power required to effect the mixing action.

Other modes of applying the principle of the invention may be employed, change being made as regards the details described, provided the features stated in any of the following claims, or the equivalent of such, be employed.

I therefore particularly point out and distinctly claim as my invention:

1. The method of preparing a homogeneous mixture of a liquid with another substance which comprises agitating the substance in a spray of the liquid to form an unstable intimate mixture, impounding a quantity of said unstable mixture centrally of a rotating member, radially displacing said impounded mixture in a continuous film, centrifugally attenuating said continuous film, while mechanically supported on one side only, and then collecting said film.

2. The method of preparing a stable mixture of asphalt and naphtha which comprises heating the asphalt to a temperature of from about 250° F. to about 400° F., agitating the asphalt in a spray of the naphtha to form an unstable intimate mixture, homogenizing said unstable mixture by attenuating the same into a film, and then collecting the film.

3. The method of preparing a homogeneous substantially stable mixture of a material such as asphalt and a liquid such as naphtha which comprises agitating the material in a spray of the liquid to form an intimate but unstable mixture, homogenizing such unstable mixture by attenuating the same into a film, and then collecting such film.

MEAD CORNELL.
